UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

DRY-PIPE VALVE.

1,411,921.

Specification of Letters Patent. Patented Apr. 4, 1922.

Application filed February 28, 1918. Serial No. 219,572.

To all whom it may concern:

Be it known that I, ALBERT J. LOEPSINGER, of the city and county of Providence and State of Rhode Island, have invented 5 certain new and useful Improvements in Dry-Pipe Valves; and I do hereby declare the following specification, taken in connection with the accompanying drawings, forming a part of the same, to be a full, 10 clear; and exact description thereof.

The invention relates to improvements in dry-pipe valves for use in automatic sprinkler systems and has for its principal object the provision of a novel form of latch 15 for preventing the valve from closing when it is once open.

A further feature of the invention consists in providing a connection between the latch and drip-valve so that each will operate simultaneously.

A further feature relates to a novel form of connection between the air-valve and the water-valve.

To these ends the invention consists in 25 the novel construction and arrangement of parts hereinafter described and more particularly set forth in the claims. In describing the invention in detail reference will be had to the accompanying drawings 30 in which

Fig. 1 is a longitudinal sectional view of a dry-pipe valve embodying my novel improvements and showing the valve in open position.

Fig. 2 is a similar view showing the valve in closed position.

Fig. 3 is a fragmentary sectional view showing a modified construction of the drip-valve.

Fig. 4 is a detail view.

Referring to the drawings, 1 represent the valve-casing which is provided with an inlet opening 2, adapted to communicate with a water supply pipe, and an outlet opening 3 adapted to communicate with the riser of a sprinkler system. The inlet opening is provided with a valve-seat 4 for the water-valve 5 and the casing is provided upon its interior with an angularly arranged valve-seat 6 for the air-valve 7.

The air-valve 7 is arranged at an angle to the water-valve 5, and is carried by a pair of swinging arms 8, which are pivoted at one end to the valve-casing by a pivot-pin 9

and the other ends of which are secured to 55 the air-valve by a pin 10. Said arms 8 are also secured to the air-valve 7 intermediate their ends by bolts 11 extending through lugs 12. The air-valve 7 is preferably provided with an annular lip 13 of flexible or 60 yielding material, which may be secured to the body of said air-valve by screws 14, said lip 13 constituting the part which seats upon the valve-seat 6.

The body of the air-valve is made of irregular shape, the central portion thereof extending horizontally and substantially parallel with the water-valve. Screwed into the bottom of this horizontal portion 15 is a cup or socket 16 which receives a correspondingly curved projection or ball 17 formed upon the top of the water-valve. Surrounding this ball portion of the water-valve is an annular boss or projection 18, and an annular space 19 between the boss 75 and said ball portion, and into the top of this annular boss is screwed a ring 20, the inner portion of which overlies a flange 21, formed on the bottom of the cup or socket 16.

As will be seen, the above construction not only enables the water-valve and air-valve to be readily and properly assembled, but also provides a rocking connection between said valves and thereby facilitates the proper seating of the water-valve.

The valve casing 1 is provided with a hand-hole cover 22, through which the valve structure may be inserted in, or removed from the valve casing and with an opening 23 in alignment with the inclined air-valve 90 seat for use in grinding said seat. The opening 23 is closed by a suitable plug 24. A drip opening 25 communicates with the intermediate chamber 26 between the two valve-seats for the purpose of taking care 95 of leakage past either the water-valve or the air-valve, said drip opening being provided with a drip-valve 27, as shown.

Said drip-valve 27 is adjustably mounted in the bottom of weight 28, by means of the screw-threaded stem 29. The weight 28 is mounted in slidable engagement with the valve-casing by means of an arm 30 secured to the outer side of said weight which is mounted to slide in a guideway 31 secured 100 upon the inside of the casing, as shown in Fig. 4. Secured upon the inner side of the weight 28 is a latch-member 32 which is ar-

ranged and adapted to cooperate with a second latch-member 33 secured to, or formed upon, the air-valve 7, for the purpose of holding the valve structure in open position and preventing it from accidentally closing again after it has once opened, or partially opened.

For this purpose the latch-member 32 is provided with a vertical side portion 34 and a beveled bottom portion 35, while the second latch member 33 is provided with a vertical side-portion 36 and a horizontal top portion 37. When the valves are in closed position, the beveled bottom portion 35 of the latch-member 32 will rest upon the outer edge of the top portion 37 of the latch member 33, and the drip-valve 27 will be held in open position, all as shown in Fig. 2.

When said valves are moved to open position, the latch-member 33 will slide along the beveled bottom portion 35 of the latch-member 32 until it moves out of engagement therewith, whereupon the latch-weight 28 will drop downward and close the drip-valve 27, and also move the latch-member 32 into the position shown in Fig. 1, with its vertical side 34 engaging the vertical side 36 of the latch-member 33, thereby serving to latch the valves in their open position and to prevent their being accidentally closed. The drip-valve 27 is provided with a downwardly extending finger-piece 37 which can be reached through an opening 38, in the top of the drip-pipe 39, and the latch can be reset by simply pressing upward on the finger-piece 37 until the latch members 32 and 33 are disengaged so as to permit the valves to close upon their respective seats.

Fig. 3 shows a modified construction in which a loose connection is provided between the drip-valve and the latch-weight to obviate any injury to the drip-valve or its seat caused by the hammering action between the drip-valve and its seat when said drip-valve is closed by the fall of the latch-weight. In said modification the drip-valve comprises a screw-threaded valve stem 29' which is adjustably mounted in the latch-weight 28 and a valve 27' having an upward extension provided at its free end with a rounded head 40 loosely mounted in a socket 41 formed in the valve stem 29'. The rounded head 40 is held in the socket 41 by means of a bushing 42 screwed therein. With this construction it will be seen that, while the fall of the latch weight 28 will serve to move the drip valve 27' toward its seat, the downward movement of the weight will be arrested just before the drip valve reaches its seat, and so that the final seating of the drip-valve will be effected by the water pressure acting thereon. The downward movement of the latch-weight 28 is arrested by a frame or cage 43 surrounding the drip opening 25, this modified construction being such that

the water pressure will have access to the top of the drip valve.

With the above described construction it will be seen that, by reason of the fact that the latch and drip-valve are connected together, they will both operate simultaneously when the valve opens and furthermore that the latch weight will assist in closing the drip-valve should said drip-valve have become stuck or otherwise obstructed in its movement. It will also be seen that the latch may be easily and quickly reset without removing any portion of the valve casing. It will be understood that I do not wish to limit myself to the exact construction and arrangement of parts hereinbefore described as various changes may be made without departing from the spirit and scope of the invention as set forth in the claims.

It will also be seen that with my novel construction and connection between the water-valve and air-valve a removable socket is provided which can be easily and readily changed when it becomes worn or damaged by constant use.

What I claim as my invention and desire to secure by Letters Patent is:

1. A dry-pipe valve comprising a casing, a water-valve and an air-valve with seats therefor, a drip-valve and closing means connected to said drip-valve and arranged and adapted to prevent the accidental closing of said water-valve and air-valve.

2. A dry-pipe valve comprising a casing, a water-valve and an air-valve with seats therefor, a drip-valve, and closing means therefor comprising a latch arranged and adapted to operate on said water and air-valves to latch them open when the drip-valve operates.

3. A dry-pipe valve comprising a casing, a water-valve and an air-valve with seats therefor, a drip-valve, closing means therefor, and a latch connected to said drip-valve closing means and actuated thereby to hold one of the other valves open.

4. A dry-pipe valve comprising a casing with water and air valves therein; a drip-valve, normally open when the air and water valves are closed; closing means for the drip-valve, additional to the closing effect of its own weight and resistance to flow of water; and means whereby said closing means is held in restraint by the closed other valves, and is released to close the drip positively by the opening of the said other valves.

5. A dry-pipe valve comprising a casing, a water-valve and an air-valve with seats therefor, a weight slidably mounted upon the interior of said casing, and a drip-valve and latch carried by said weight.

6. A dry-pipe valve comprising a casing, a water-valve and an air-valve with seats

- therefor, a latch-member carried by said air-valve, a weight slidably mounted within said casing, and a latch-member and drip valve carried by said weight.
- 5 7. A dry-pipe valve comprising a casing, a water-valve and an air-valve with seats therefor, a weight slidably mounted within said casing, and a drip-valve adjustably mounted in said weight.
- 10 8. A dry-pipe valve comprising a casing, a water-valve and an air-valve with seats therefor, a weight slidably mounted within said casing and a latch-member and a drip-valve carried by said weight, said latch-member being provided with a tapered portion arranged and adapted to engage the air-valve when it is in closed position.
- 15 9. A dry-pipe valve comprising a casing, a water-valve and an air-valve with seats therefor, a weight slidably mounted within said casing, and a latch-member and drip-valve carried by said weight, said latch-member being provided with a tapered portion arranged and adapted to engage said air-valve when it is in closed position and to be moved out of engagement when said air-valve opens.
- 20 10. A dry-pipe valve comprising a casing, a water-valve and an air-valve with seats therefor, a weight slidably mounted within said casing, and a latch member and drip-valve carried by said weight, said latch-member being provided with a portion arranged and adapted to be automatically moved into the path of movement of said air-valve when said air-valve opens.
- 25 11. A dry-pipe valve comprising a casing, a water-valve and an air-valve with seats therefor, a latch member carried by said air-valve, a weight slidably mounted within said casing, and a second latch-member and drip-valve carried by said weight, said last mentioned latch-member having a tapered bottom portion engaging the top of said first latch-member when the air-valve is in closed position and having a vertical side-portion arranged to be engaged by a corresponding vertical side-portion upon said first mentioned latch-member when said air-valve moves toward closed position.
- 30 12. A dry-pipe valve comprising a casing, a water-valve and a coacting air valve, one of said valves having a bowl member and the other having a ball with surrounding ring, adapted respectively to engage the inner side and the outer side of the bowl, whereby the two valves are held together with self adjusting bearing.
- 35 13. A dry-pipe valve comprising a casing, a water-valve and an air-valve with seats therefor, said air-valve being provided with a removable socket, and said water-valve being provided with a ball-projection formed integral therewith and means for securing said ball-projection in said socket.
- 40 14. A dry-pipe valve comprising a casing, a water-valve and an air-valve with seats therefor, said air-valve being provided with a socket-member secured therein, and said water-valve being provided with an integral ball-member, and adjustable means for securing said ball-member in said socket-member.
- 45 15. A dry-pipe valve comprising a casing, a water-valve and an air-valve with seats therefor, said air-valve being provided with a socket-member secured therein, and said water-valve being provided with an integral ball-member and a boss surrounding said ball-member, and a ring-member mounted on said boss and arranged to overlie said socket-member.
- 50 16. A dry-pipe valve comprising a casing, a water-valve and an air-valve with seats therefor, said air-valve being provided with a socket-member removably secured therein and having an annular flange upon the exterior thereof, and said water-valve being provided with an integral ball-member and an annular boss surrounding said ball-member, and a ring-member removably mounted on said boss and overlying the annular flange upon the socket-member.
- 55 17. A dry-pipe valve comprising a casing, a water-valve and an air-valve with seats therefor, said air-valve being provided with a socket-member removably mounted therein and having an annular flange upon the exterior thereof, and said water-valve being provided with an integral ball-member, an annular boss surrounding said ball-member, an annular recess between said boss and ball-member, and a ring-member adjustably mounted in said boss and having its inner portion overlying the annular flange upon the socket-member.
- 60 18. A dry-pipe valve comprising a casing, a water-valve and an air-valve with seats therefor, a drip-valve and seat, a weight for moving said drip-valve to its seat, and a loose connection between said weight and drip-valve.
- 65 19. A dry-pipe valve comprising a casing, a water-valve and an air-valve with seats therefor, a drip-valve and seat, a weight for moving said drip-valve to its seat, and means for arresting the movement of said weight before the drip-valve reaches its seat.
- 70 20. A dry-pipe valve comprising a casing, a water-valve and an air-valve with seats therefor, a drip opening, a drip-valve and seat, a weight for moving said drip-valve to its seat, and a stop for limiting the movement of said weight in one direction.
- 75 21. A dry-pipe valve comprising a casing, a water-valve and an air-valve with seats therefor, a drip-opening, a drip-valve and seat, a weight for moving said drip-valve to its seat, and a frame surrounding said drip-opening.

22. A dry-pipe valve comprising a casing, a water-valve and an air-valve with seats therefor, a drip opening, a drip-valve and seat, a weight for moving said drip-valve to its seat, and a stop for the weight, associated with the drip-valve seat; there being lost motion in the connection between the weight and the drip-valve; and said stop being at a level to stop the weight after the drip-valve has closed and during said lost motion.
23. A dry-pipe valve comprising a casing with water and air valves, a drip valve, and means, connected to the drip valve, arranged and adapted to prevent accidental closing of one of the first said valves.
24. A dry-pipe valve comprising a casing with water and air valves, a drip valve, and a latch for one of the first said valves, arranged and adapted to operate when the drip valve operates.
25. A dry-pipe valve comprising a casing with water and air valves, a drip valve and a latch for one of the first said valves connected to said drip valve.
26. A dry-pipe valve comprising a casing with water and air valves, an intermediate chamber and a drip valve therefrom, combined with a latch in the chamber arranged and adapted to operate simultaneously with the drip valve.
27. A dry-pipe valve comprising a casing, with water and air valves and an intermediate chamber, combined with a latch for said valves and a drip passage for the chamber having a valve interlocked with the latch.
28. A dry-pipe valve comprising a casing with water and air valves, a drip passage, a drip valve and seat, a weight for moving the drip valve to its seat, and a stop for the weight, associated with the drip-valve seat; there being lost motion in the connection between the weight and the drip-valve; and said stop being at a level to stop the weight after the drip-valve has closed and during said lost motion, combined with means holding the drip valve open, said means being itself held by the air and water valves when they are closed.
29. A dry-pipe valve comprising a casing with water and air valves, a drip passage from the space between them, with a valve arranged and adapted to close automatically, combined with means holding the drip valve open, said means being itself held by the air and water valves when they are closed, and being adapted, when released by their opening, to move into position latching one of them open and permitting closure of said drip valve.
30. A dry-pipe valve comprising a casing with water and air valves and intermediate chamber having a vent to atmosphere, combined with means adapted to close the vent, held in restraint by the closed water and air valves.
31. A dry-pipe valve comprising a casing with water and air valves and intermediate chamber having a vent to atmosphere, combined with means adapted to close the vent on the opening of said valves; and means to obstruct the closing of the valves after thus being opened; said vent closing means being arranged tending to actuate said obstructing means.
